UNITED STATES PATENT OFFICE.

HENRY GEORGE SCHATZ, OF COMMERCE, MISSOURI, ASSIGNOR OF ONE-HALF
TO WILLIAM HARRY HUTTON, OF SAME PLACE.

CHURN.

SPECIFICATION forming part of Letters Patent No. 629,274, dated July 18, 1899.

Application filed March 30, 1898. Serial No. 711,102. (No model.)

To all whom it may concern:

Be it known that I, HENRY GEORGE SCHATZ, a citizen of the United States, residing at Commerce, in the county of Scott and State of Missouri, have invented new and useful Improvements in Churns, of which the following is a full, clear, and exact description.

My improvement relates to that class of churns which employs a vibrating dasher; and it has for its object such a churn in which the stroke of the dasher will be capable of being regulated to suit different size churn-bodies and in which the operating mechanism will be of few parts and efficient in operation.

With these ends in view my invention consists in certain details of construction and combinations of parts which I shall first describe, and then point out the novel features in the appended claims.

Reference is to be had to the accompanying drawings, in which—

Figure 1 is a side elevation of my improved churn, the lower part of the churn-body being broken away to show the dasher. Fig. 2 is a view similar to Fig. 1, but at right angles thereto and with the lower half of the churn-body omitted. Fig. 3 is a horizontal section taken approximately on the line 3 3 of Fig. 1. Fig. 4 is a detail plan view illustrating the dasher. Fig. 5 is a vertical section on the line 5 5 of Fig. 4. Fig. 6 is a detail view on the line 6 6 of Fig. 1; and Fig. 7 is a section on the line 7 7, Fig. 1.

On the top of the churn-body A is placed the cover B, in which all the working parts of the churn are mounted. Supported on the cover B are two vertical supports C, at the upper end of which a worm-box D is somewhat loosely held by having its ends d journaled in the upper end of the said support. Through a vertical opening in the worm-box is fitted to move the worm-shaft E, to whose lower end the upper end of the dasher-shaft F is securely fastened. The dasher G, consisting of the blades g, provided with openings g', is held on the lower end of the dasher-shaft F, and just above the blade g is placed the disk-like air-cup g². Now it will be seen that when the worm-shaft E moves up and down in the worm-box D the dasher-shaft F

will also move up and down through an opening in the cover B and at the same time will rotate, thereby causing the dasher-blades to break the globules in the milk, and the air-cup g² will force the cream to the top, expediting the separation of the butter.

To operate the worm-shaft E and its accompanying parts, I employ the following mechanism: An arm H extends horizontally out from one support C, and a sleeve h is fitted to slide on the arm H, the said sleeve having pivotally mounted thereon the rocking lever h', on which is fitted to slide a second sleeve h². Pivotally connected with this sleeve h² is one end of a handle J, and intermediate of its ends the handle is formed with openings j, in one of which is pivotally secured an L-shaped shoe K, whose smaller member is bifurcated to straddle the dasher-shaft F, being held in place by two collars k' and k², secured on the shaft at the point of its connection with the worm-shaft.

To securely hold the parts on the churn-body, I preferably provide the latter with an annular flange L, with which is adapted to engage a depending hook M on each side of the cover, the upper ends of the hook being screw-threaded and provided with thumbscrews N, whereby to fasten the hooks to the flange.

It is obvious that when the handle J is reciprocated the shoe K will cause the up-and-down movement of the worm-shaft and dasher-shaft, and the stroke will be proportionate to the position the sleeves h² and h occupy on the rocking lever h' and arm H, respectively. In order, therefore, to lengthen or shorten the stroke, I move said sleeves toward the free ends of the rocking lever and arm or away from the same in order to obtain the length of stroke desired, and when the sleeves have been so adjusted they are securely fixed in place by set-screws h³ and h⁴. To further aid in this adjustment, I have provided the plurality of openings j, any one of which is adapted to receive the end of the shoe K.

It will be observed that I have provided a churn which will be very efficient in operation and which is adapted to a wide range of usefulness by reason of the features of ad-

justment. Further, it will be noticed the hooks M can be caught around the ordinary ears of a stone jar, if desired to use the churn-operating mechanism in connection with such 5 a churn-body, and can be easily detached when the butter is formed.

Having thus described my invention, what I claim, and desire to secure by Letters Patent, is—

- 10 1. In a device of the character described, the dasher-shaft, the worm-shaft secured to said dasher-shaft, a handle for operating the worm-shaft, a rocking lever on which the end of the handle is adjustably and pivotally mounted, means for securing the said end in adjusted positions, a support for said rocking lever, and means for adjusting said lever on said support, as and for the purpose as set forth.
- 20 2. The combination with a churn-body and the cover therefor, of supports on said cover, a worm-shaft mounted to move up and down between said supports and having the dasher-shaft connected therewith, an arm extended from one of said supports, a rocking lever adjustably mounted on said arm and having means for securing it at different points along the arm, and an operating-handle having one end pivoted to and adjustably held on the 25 said rocking lever and being connected to the worm-shaft to move the same, as set forth.
- 30 3. The combination with a churn-body and the cover therefor, of supports on said cover, a worm-box loosely held between said supports, a worm-shaft fitted in said worm-box and connected with a vertical shaft, an arm extended from one of said supports, a sleeve fitted to slide on said arm, a rocking lever carried by said sleeve, a second sleeve fitted 35 to slide on said rocking lever, an operating-

handle pivotally connected to said last-named sleeve and secured to the worm-shaft to move therewith, and means for securing said sleeves in different positions on the arm and rocking lever, as and for the purpose set forth. 45

4. In a churn, the combination with the body, its cover and dasher-shaft, of the vertical supports on said cover, the worm-box journaled between said supports, the worm-shaft fitted to move up and down in said box 50 and secured to said dasher-shaft, a horizontal arm on one of said supports, a rocking lever having one end arranged to be held at different points along said arm, an operating-handle having one end arranged to be held at different points along said rocking lever, and a bifurcated L-shaped shoe having one member pivotally secured to the said handle, the bifurcated member of said shoe loosely embracing said dasher-shaft and being held 55 thereon, whereby to move the worm-shaft up and down, as and for the purpose set forth. 60

5. In a device of the character described, the dasher-shaft, the worm-shaft secured thereto whereby to reciprocate and rotate the dasher-shaft, a handle for operating the worm-shaft, the said handle being connected to said worm-shaft between the ends of the handle, a rocking lever on which an end of the handle is pivotally mounted, and means for adjusting the said end of the handle on the rocking lever and securing it in adjusted positions, whereby to shorten or lengthen the stroke of the worm-shaft, as and for the purpose set forth. 65 70
